UNITED STATES PATENT OFFICE.

PAUL CARLSON, OF MUSKEGON HEIGHTS, MICHIGAN.

DRIVING MECHANISM FOR WASHING MACHINES.

Application filed August 2, 1923. Serial No. 655,165.

This invention relates to driving mechanisms for washing machines and concerns itself primarily with an organization having a novel form of clutching mechanism for connecting the driving member with the driven member.

The invention comprises the novel mechanism and combinations hereinafter described and more particularly pointed out and defined in the appended claims.

In the accompanying drawings which illustrate a preferred embodiment of this invention and in which similar reference numerals refer to similar features in the different views:

Figure 1 is a top plan view of a washing machine embodying my invention with the cylinder shown in dotted lines.

Figure 2 is a fragmentary sectional view taken substantially upon the line 2—2 of Figure 1 with parts in elevation.

Figure 3 is an enlarged sectional view taken substantially upon the line 3—3 of Figure 2.

Figure 4 is a sectional view upon the line 4—4 of Figure 3 with parts in elevation.

Figure 5 is a sectional view upon the line 5—5 of Figure 3.

Figure 6 is a sectional view upon the line 6—6 of Figure 3 with parts in elevation.

Figure 7 is a sectional view upon the line 7—7 of Figure 3 with parts in elevation.

As shown in the drawings: There is shown in dotted lines, a rotary washing machine cylinder 1 which is oscillated backwards and forwards by the driving mechanism which is connected to the central spindle support of the cylinder.

This driving mechanism consists of a motor 2 which is supported beneath the cylinder. The motor shaft 3 is geared in any appropriate way (not shown) to a shaft 4 suitably journaled in the frame of the washing machine. An eccentric 5 is secured upon the shaft 4 and the eccentric strap that surrounds the eccentric is provided with an arm 6 which extends upwardly and is pivotetd to an oscillating lever 7 which is loosely journaled upon a shaft 8 supported at one end in a stationary transverse frame member 9 of the washing machine. The shaft 8 is provided with a collar 10 that bears against the bearing member 9 and beyond the collar 10, a hollow cylindrical clutch member 11 is rotatably mounted upon said

shaft 8. The end of the clutch member 11 extends beyond the end of the shaft 8 and is provided with polygonal aperture 12 coaxial with said shaft for receiving the aforementioned spindle of the washing machine cylinder. The hollow clutch member 11 is provided with an opening 13 (Figure 4) through which the lever freely extends; the opening being considerably larger than the lever so that the latter may oscillate to a certain extent without striking the walls of said opening. The lever 7 is also provided with arcuate guide wings or flanges 14 that partially surround the hollow clutch member 11 and provide an additional bearing support 70 or surface for the lever.

The hollow clutch member 11 is further provided with a longitudinally extending slot 15 upon the center line of the slot 13 and the lever 7 is likewise provided with a slot or mortise upon its inner side as indicated at 16 in Figure 6. A clutch key or member as 17 is positioned so as to slide in the slot 15 and its end is so fashioned as to readily enter the slot or mortise 16 in the lever 7.

The clutch key 17 has a right angled extension or tail 18 that extends through an arcuate and vertically extending guide slot 19 in a hammer ring 20 that surrounds a portion of the clutch sleeve 11 and forms a bearing therefor. A pin 17^a extends through the end of the extension and retains the clutch key in position. The hammer ring 20 is integral with a rod 21 that is 90 slidingly mounted in the frame member 9 and its outer end slides through a recess in an end supporting block 22. A pin 23 extends through the rod 21 and a coil spring 24 is confined between the block 22 and the pin 23 which normally tends to project the rod 21 toward clutching position.

The rod 21 is normally held in clutching position by the spring 24 with the clutch key 17 in operative engagement with the lever 7. But the rod 21 may, however, be retracted from such position by a sliding actuator 25 which is suitably supported adjacent the beam 9 and is provided at its remote end with a wedge shaped formation 105 that engages the pin 23 and slides the rod 21 into inoperative position when the actuator is properly operated. For operating the actuator, a lever 26 is pivoted intermediate its ends to a block 27 upon the beam 9, the

lower end of said lever being pivoted in a bifurcation formed in the end of the actuator.

The operation is as follows: In the operation of the washing machine by the aforementioned driving mechanism, the motor will rotate the eccentric which will oscillate the lever 7 through the eccentric arm 6. Now, assuming that the actuator 25 has been retracted so that the spring 24 will have shifted the clutch key 17 into the slot or mortise 16 in the lever 7 it is evident that the clutch cylinder 11 will partake of the oscillations of the lever 7 and oscillate the washing cylinder which is connected to the clutch cylinder 11, the clutch key 17 forming the connection between the lever 7 and clutch cylinder 11. When it is desired to declutch the driving mechanism from the cylinder, the actuator 25 is shifted to retract the rod 21 and hammer ring 20 whereby the clutch key 17 is retracted from its engagement with the lever 7.

I am aware that many changes may be made, and numerous details of construction may be varied through a wide range without departing from the principles of this invention, and I therefore do not purpose limiting the patent granted hereon, otherwise than necessitated by the prior art.

I claim:

1. In a washing machine drive, a stationary support, a cylindrical member rotatable upon said support and adapted for clutching relation with a member to be driven, an oscillating member upon said support, means connecting said oscillating member and cylindrical member for conjoint oscillation, and means for actuating said first means to disconnect said cylindrical member from operative connection with said oscillating member, said first means comprising

ing a ring surrounding said support, and a key member adapted to be actuated into engaging position by said ring but adapted to oscillate with respect thereto.

2. In a washing machine drive, a stationary support, a cylindrical member rotatable upon said support and adapted for clutching relation with a member to be driven, an oscillating member upon said support, means connecting said oscillating member and cylindrical member for conjoint oscillation, and means for actuating said first means to disconnect said cylindrical member from operative connection with said oscillating member, said second means comprising a spring impelled member rigidly secured to said first means and a wedge shaped lever adapted to retract said spring impelled member.

3. In a washing machine drive, a stationary support, a cylindrical member rotatable upon said support and adapted for clutching relation with a member to be driven, an oscillating member upon said support, means connecting said oscillating member and cylindrical member for conjoint oscillation, and means for actuating said first means to disconnect said cylindrical member from operative connection with said oscillating member, said first means comprising a ring surrounding said support, a key member adapted to be actuated into engaging position by said ring but adapted to oscillate with respect thereto, said second means comprising a spring impelled member rigidly secured to said ring and a wedge shaped lever adapted to retract said spring impelled member.

In testimony whereof I have hereunto subscribed my name.

PAUL CARLSON.
